ATTORNEY

UNITED STATES PATENT OFFICE.

DAVID D. TORPEY, OF NEW YORK, N. Y.

DESIGN FOR A HARNESS-SUPPORT.

SPECIFICATION forming part of Design No. 31,595, dated October 8, 1899.

Application filed September 1, 1899. Serial No. 729,258. Term of patent 14 years.

To all whom it may concern:

Be it known that I, DAVID D. TORPEY, a citizen of the United States, residing at New York, (Brooklyn,) county of Kings, and State of New York, have invented and produced a new and original Design for a Harness-Support, of which the following is a specification, reference being had to the accompanying drawings, forming part thereof.

Figure 1 is a plan view of a harness-support, showing my new design; and Fig. 2 is an end view thereof.

As shown in the drawings, the leading or material feature of my design consists of a body substantially cylindrical in form, which is provided at the free end thereof with a

flange 5 and intermediate of its length with a second flange 6, dividing the said body into two parts 8 and 9. The essential features of my design are the two flanges on a body substantially cylindrical in form, one of which is intermediate of its length. 20

Having described my invention, what I claim as new, and desire to secure by Letters Patent, is—

The design for a harness-support, as herein shown and described.

DAVID D. TORPEY.
